VELOCIPEDE FORK

Wilfred G. Johnson and Maurice E. Hendricks,
Elyria, Ohio, assignors to Hall Kirkham, Elyria,
Ohio, receiver for The Colson Company, Elyria,
Ohio, a corporation of Ohio

Application December 28, 1933, Serial No. 704,247

8 Claims. (Cl. 208—96)

This invention relates to velocipedes, bicycles, and similar vehicles and more particularly to the construction of the front forks of children's velocipedes.

Heretofore the front forks of such velocipedes have ordinarily been made of malleable castings which are quite heavy and expensive. According to our invention the fork and crown members are made of stampings, and it is among the objects of our invention to provide a fork construction formed of pressed metal parts and having great strength and rigidity. Another object of our invention is to provide a pressed metal fork construction which can be readily and economically manufactured and assembled.

Further objects and advantages of our invention will become apparent from the following description of a preferred form thereof, reference being made to the accompanying drawing. The essential characteristics are summarized in the claims.

Briefly, a fork made according to our invention preferably comprises a hollow pressed metal crown member which is pressed onto the tubular stem to which the handle bars are attached, and a pair of concave or channeled fork members. The forks are preferably welded to depending tongues formed integrally with the crown, and at their upper ends the forks are provided with inwardly turned portions which are preferably arc welded to the end of the stem. The arrangement is such that the crown engages the stem in a zone spaced apart from the engagement of the ends of the forks therewith so that a very rigidly braced construction is obtained.

Referring to the drawing, Figure 1 is a side elevation illustrating our fork construction, the lower ends of the fork and the upper end of the stem portion being broken away; Figure 2 is a front elevational view, partially in section, of the parts shown in Figure 1; Figure 3 is a perspective of one of our fork members before assembly with the crown and stem; and Figure 4 is a section of one of the fork members as indicated by the line 4—4 of Figure 3.

As shown in the drawing, the stem 10 to which the handle bars are attached preferably comprises a piece of steel tubing. The crown of the fork comprises a hollow stamping 11 having depending tongues 12 on either side and having a deeply drawn portion as indicated at 13 to increase the rigidity of the depending tongues. A raised boss 14 is formed centrally of the crown member and is provided with an opening 15 which

is adapted to receive the stem 10, the stem making a pressed fit within the opening.

The forks 16 are concave pressed metal channel section members which taper gradually from the upper end 17 to the lower end 18. To improve the appearance of the forks, the base of the channel is preferably curved slightly, as indicated in Figure 4. The lower ends 18 of the forks may be provided with openings 19, or other suitable means, to receive the ends of the wheel axle, while the upper ends 17 of the forks are provided with inwardly turned portions 20 which are secured to the lower end of the stem 10. The side walls of the channel section of the forks are preferably thickened or widened slightly, as indicated at 21, in the region where the ends of the forks are bent inwardly, in order to provide reinforcing fillets in the forks and thereby to increase the rigidity thereof.

As shown in Figure 2, the forks preferably are secured to the tongues 12 of the crown member by spot welding, as indicated at 25, and the ends 26 of the inwardly turned portions 20 of the forks are preferably arc welded to the end portion of the stem 10 as indicated at 27. It is to be particularly noted that the ends 26 engage the stem 10 in a zone spaced away from the engagement of the crown member with the stem 10. The vertical load on the fork is, of course, largely taken by the arc welded joints between the forks and the stem 10, while the lateral forces are absorbed both by the arc welded joints and by the engagement of the stem 10 with the crown member 15. By this construction, the integrally joined crown and fork members brace each other with respect to the stem, thus producing an extremely rigid and strong fork. Furthermore, the tongues 12 reinforce the upper portions of the forks and further increase the rigidity of the entire construction.

In order to provide a convenient means for attaching and supporting a fender or mud guard to our fork, we preferably place a pin 28 through suitable oppositely disposed openings in the stem 10. The fender (not shown) may be supported by any ordinary means from the pin. The pin, of course, must be positioned before the crown is assembled on the stem and if desired the pin can be used as a convenient gauge or stop to properly position the crown with respect to the end of the stem, the ends of the pin abutting the lower surface of the boss 14 of the crown.

From the foregoing description of a preferred form of our invention, it will be seen that our fork is extremely rigid and can be manufactured

very economically as it comprises merely a piece of tubing for the stem, a pressed metal crown member, and a pair of pressed metal forks. The fork construction can be assembled readily by 5 pressing the crown member into position on the stem and thereafter spot welding the fork members to the depending tongues of the crown member and welding the inturned upper ends of the forks to the lower end of the stem. The manufacturing and assembling operations can be carried out rapidly with minimum expenses and the completed fork is exceptionally strong and rigid. It will be evident to those skilled in the art that 10 various modifications and changes can be made in the particular construction disclosed herein, all without departing from the spirit and scope of our invention. Accordingly it is to be understood that our patent is not limited by the disclosure herein or in any manner other than by the 15 appended claims when given the range of equivalents to which our patent may be entitled.

We claim:—

1. In a fork construction for velocipedes, bicycles and the like, the combination of a tubular stem, a pressed metal crown member, having a raised central boss surrounding and tightly engaging the stem, and having downwardly extending oppositely disposed tongues, and a pair of pressed metal fork members disposed within said crown member and permanently secured to said tongues, said fork members having inturned upper ends extending inwardly away from said tongues and below said central boss and being welded to said stem in a zone spaced apart from the zone of engagement of said crown member with said stem, whereby said forks and said crown member are rigidly mounted on said stem and braced with respect thereto.
2. In a fork construction for velocipedes, bicycles and the like, the combination of a tubular stem, a pressed metal crown member mounted on and tightly engaging the stem, said crown member having downwardly extending oppositely disposed tongues, and a pair of pressed metal fork members disposed within said crown member and permanently secured to said tongues, said fork members having inturned upper ends extending inwardly away from said tongues and being welded to said stem in a zone spaced apart from the zone of engagement of said crown member with said stem, whereby said forks and said crown member are rigidly mounted on said stem and braced with respect thereto.
3. In a fork construction for velocipedes, bicycles, and the like, the combination of a tubular stem, a hollow pressed metal crown member mounted on and tightly engaging the stem in a zone spaced above the lower end thereof, and a pair of pressed metal fork members disposed within said crown member and permanently joined thereto, said fork members having inturned upper ends spaced apart from adjacent

portion of said crown member, said ends being welded to the lower end of said stem and thereby engaging said stem in a zone remote from the zone of engagement of said crown member with said stem.

4. In a velocipede fork construction, a tubular stem, a pressed metal crown member having a raised central boss provided with an opening through which said stem projects, said crown member also having downwardly extending oppositely disposed tongues, and fork members spot-welded to said tongues, said fork members comprising channel section stampings having inturned upper ends, said inturned ends being welded to said stem in a zone spaced apart from the zone of engagement of said crown member with said stem.

5. In a velocipede fork construction, a tubular stem, a pressed metal crown member having an opening through which said stem projects, and having downwardly extending oppositely disposed tongues, and fork members spot-welded to said tongues, said fork members comprising channel section stampings having inturned upper ends, the said inturned ends being welded to said stem in a zone spaced apart from the zone of engagement of said crown member with said stem.

6. In a fork construction for velocipedes, bicycles and the like, the combination of a tubular stem, a hollow pressed metal crown member mounted on and tightly engaging the stem in a zone spaced from the lower end thereof, and a pair of pressed metal fork members permanently joined to said crown member, said fork members having inturned upper ends, said ends being welded to the lower end of said stem and thereby engaging said stem in a zone remote from the zone of engagement of said crown member with said stem.

7. In a fork construction for velocipedes, bicycles and the like, the combination of a tubular stem, a hollow pressed metal crown member mounted on and tightly engaging the stem, and a pair of pressed metal fork members secured to said crown member, the upper ends of said fork members being welded to said stem in a zone spaced apart from the zone of engagement of said crown member with said stem.

8. In a fork construction for velocipedes, bicycles and the like, the combination of a tubular stem, a hollow pressed metal crown member mounted on and tightly engaging the stem and having oppositely disposed depending tongues, and a pair of pressed metal fork members permanently secured to said tongues, the upper ends of said fork members being welded to said stem in a zone spaced apart from the zone of engagement of said crown member with said stem.
